UNITED STATES PATENT OFFICE.

CHARLES W. WORTHINGTON, OF RUSHVILLE, ILLINOIS.

ADJUSTABLE-SCALE STOCK-RACK.

1,047,725.

Specification of Letters Patent. Patented Dec. 17, 1912.

Application filed October 31, 1911. Serial No. 657,843.

To all whom it may concern:

Be it known that I, CHARLES W. WORTHINGTON, a citizen of the United States, residing at Rushville, in the county of Schuyler and State of Illinois, have invented certain new and useful Improvements in Adjustable-Scale Stock-Racks, of which the following is a specification.

This invention relates to adjustable scale stock racks, and has for one of its objects to provide a simply constructed device which may be closed to retain the stock upon the scale platform and which may be opened to permit the stock to pass off from the scales, and the parts likewise arranged to be moved outwardly at any desired angle to enable the scales to be employed for weighing merchandise such as hay, grain and the like.

Another object of the invention is to provide a device wherein the parts of the rack are braced and supported while at the same time readily detachable when not in use.

With these and other objects in view, the invention consists in certain novel features of construction as hereinafter shown and described, and then specifically pointed out in the claims, and in the drawings illustrative of the preferred embodiment of the invention: Figure 1 is a perspective view of the improved device with one end closed and the other end open; Fig. 2 is a transverse section on the line 2—2 of Fig. 1; Fig. 3 is a perspective view, from beneath, of the platform; Fig. 4 is an enlarged sectional detail illustrating the construction of the brace straining device; Fig. 5 is a section on the line 5—5 of Fig. 4; Fig. 6 represents the notched bolt and handle enlarged and detached.

Corresponding and like parts are referred to in the following description and indicated in all the views of the accompanying drawings by the same reference characters.

The improved device is designed to be attached to the platform scale of the form usually designated as stock or wagon scales, or with a platform large enough to hold a wagon, and in the drawings the floor of the platform is designated by the character 10, the floor being formed of a plurality of planks extending transversely of the platform and supported by two or more longitudinal floor sills 11, the transverse floor members or planks 10 constituting the supporting platform.

The platform 10 with its sill members is

surrounded by an oblong frame 13, the latter being supported upon a suitable foundation, not shown. Extending across the ends of the floor members at the upper side are reinforcing members 14 which are designed to carry the weight of the superstructure and thus distribute the weight uniformly over all of the members 10 as hereafter explained.

Extending above the platform and its rails 14, is a rack device comprising sides and ends, the sides being mounted to swing outwardly upon the rails 14 and the ends mounted to swing from the side members. The sides of the rack are precisely alike except that they are reversely arranged, and the description of one will suffice for both. Each side of the rack is formed with vertical terminal posts 15—16, a relatively heavy upper rail 17 spaced a considerable distance below the tops of the posts, a plurality of horizontal intermediate rails 18 spaced apart, and a plurality of vertical posts 19 spaced at uniform distances apart between the end posts and secured together by any suitable means such as nails or bolts. The terminal posts and the intermediate posts extend below the lowermost of the rails 18 and are so located as to extend above the outer portions of the supporting members 14. Bearing upon the members 14 at their ends, and under one or more of the intermediate posts 19, are metal wear plates 20 having hinge members 21 at their outer edges and connected to opposing hinge members 22 attached to the posts.

Any required number of the posts may be provided with the combined wear plates and hinges, but generally the terminal posts 15—16 only will be thus hingedly connected to the members 14. It will be noted that the hinge portion of the device is at the outer edge of the members 14 and at the outer sides of the post, so that the "sides" of the rack will fold outwardly but will be prevented from folding inwardly beyond the vertical line. Attached to the inner faces of the terminal posts 15—16 are studs 23 which extend downwardly through apertures in the wear plates 20 and likewise through the members 14 and the floor members 10, and each is provided with a stop nut 24. The studs 23 extend for a considerable distance below the floor members so that the sides of the rack are adapted to be moved outwardly a distance equal to the

play of the studs 23, but will be limited in their outward movement by the engagement of the stop nuts 24 with the bottoms of floor members. By threading the studs 23 and employing the nuts 24 the latter serve as 5 adjustable stops to enable the inclination of the rack sides to be controlled to any extent within the range of the threaded portions of the studs, as will be obvious. One terminal post of each of the rack sides is 10 formed with a circular bearing 25 preferably close to the upper rail 17, and mounted to swing upon this bearing by a strap hinge 26 is a tie bar or rail 27, the bar designed to swing over the top of the capped rail 17 15 when not in use and to fit by its outer end in a recess 28 in the opposite post 16 of the opposite "side" of the rack. Each of the bars 27 is provided with an L-shaped strap 29 which forms a keeper or strap to engage 20 around the recess in the post 16 as shown, and thus lock the opposite terminal posts together.

At its upper end each of the posts 15 is 25 provided with a circular bearing 30 to correspond with the circular bearing 25, to receive the upper end of a brace 31, and serving as a hinge to work in harmony with hinge 26. The brace rod is connected at the 30 opposite end by a bolt to the rail 27. By this means it will be noted that the brace 31 will swing upon the post 15 together with the rail 27 when the latter is moved and form a support for the rail 27 at all portions 35 of its movements. Each of the rails 27 is provided with a vertical slot 32 through which a pin 33 is mounted to rotate, the pin having a portion cut away at one side as shown at 34, the cut-away coming within 40 the slot 13. Each of the pins is formed with a head 12 at one end and with a transverse threaded aperture at the other end to receive the threaded end of a handle 12. By this means the pins are mounted for 45 rotation through the rails and held from end movement by the coaction of the head 12 and the handle 35. The pins are thus readily inserted and held in position, and are also interchangeable so that the same pin 50 may be employed in either rail. Each of the posts 16 is provided at its upper end with an eye bolt 36 to swingingly support the upper end of a rod 37. At its outer end the rod 37 is formed with a downwardly directed hook 38 adapted to pass through the cut-away portion 34 of the pin 33 when the pin is turned with the handle 35 extended downwardly. By this arrangement when the arm 35 is turned in its downward position 55 the hooked terminal 38 of the rod may be inserted into the slot 32 and passed through the portion 34 of the pin, and then when the arm is turned into its upward position as shown in Fig. 1 the unmutilated portion 60 of the pin will enter the interior of the

hook 38 and thus lock the rod to the member 27 as shown in Fig. 4. By this means the two posts 15—16 of the opposite sides of the rack and the rail 27 are firmly locked together with the rack sides in vertical position, while at the same time readily detachable when required. 70

End gates are connected to the rack sides and as the gates are precisely alike, the description of one will suffice for both. Each 75 of the posts 15 is provided with hinge members 39 and each gate, represented as a whole at 40, is provided with opposing hinge members 41 engaging the hinge members of the post so that the gates are free to swing across 80 the space between the rack sides and form closures to the ends of the same. Hinged at 42 to each of the posts 16, is a latch member 43 which extends inwardly from the post when in one position and is foldable against 85 the outer face of the post when not in use. When in its inwardly projected position the member 43 forms a latch against which the free end of the gate 40 bears when in closed 90 position, and each gate is provided with a 90 hook 44 and each of the members 43 is provided with an eye 45 to receive the hook, so that the gate may be locked in its closed position. By this means the rack portion of the device is provided with effectual gate 95 closures, which bear at all points against the gate from bottom to top, each gate being arranged to bear against one of the stop members 43 and retained in position by hook and eye as shown in Fig. 1. 100

It will be noted that the hinges 39—41 are so arranged that the gates swing in both directions, and when the rack is to be used, one of the gates is closed and the other gate 105 swung outwardly to permit the stock to be driven into the rack and upon the scale platform. The gate is then closed and the member 45 folded over the gate and secured by the hook 44. Generally the stock will be removed from the rack at the opposite end 110 from which they are received, and this can readily be done by simply opening the opposite gate, as will be obvious.

When one or both of the members 27 is turned into inoperative position as shown at the right in Fig. 1, the arm 35 being turned into its downward position projects below the upper line of the rail 17 of the adjacent rack side, and thus limits the further outward movement as shown at the 120 right in Fig. 2.

When the improved rack is not required, the locking members 34—35 are released to release the rods 37 and permit the members 27 to be swung around in parallel relations to the rails 17. The gates are then likewise released and swung inwardly in parallel relations to the sides of the rack and the latch members 43 folded back against the posts 16. The sides of the rack device together with 130

the gates, which are hinged thereto, are then free to fold outwardly as far as the members 23—24 will permit, which will be sufficient to permit a load of hay or the like to be 5 driven on the scales, or the scales otherwise used as required.

The improved device is simple in construction, can be manufactured of any required size and of any suitable material and 10 applied without material structural changes to scales of various makes and sizes.

Having thus described the invention, what is claimed as new is:

1. An adjustable stock scale rack including 15 movable sides, tie bars each having a longitudinal slot and adapted to hold said sides together, a pin extending through each of said bars and the slot thereof and having the portion within the slot cut away at one side, a brace rod swinging from one of the sides and provided with a terminal hook for engagement with the unmutilated portion of the pin, and means for rotating said pin.

2. An adjustable stock scale rack including 20 swinging sides, tie bars swinging from one of said sides and provided with means for detachably engaging the other side and

each having a longitudinal slot, a pin extending through each of said bars and the slot thereof and cut away at one side within 30 the slot, a brace rod swinging from the other of the sides and provided with a terminal hook for engagement with the unmutilated side of the pin, and means for rotating said pin.

3. An adjustable scale rack including 35 swinging sides, tie bars each having a longitudinal slot and adapted to hold said sides together at the inner limit of their movement, a pin extending through each of said bars and the slot thereof, said pin having a head at one end and a detachable handle at the other end and cut away at one side intermediate the ends, and a brace rod swinging from one of the sides and provided with a 40 terminal hook for engagement with the unmutilated portion of the pin when the handle is disposed in one position.

In testimony whereof I affix my signature in presence of two witnesses.

CHARLES W. WORTHINGTON. [L. s.]
